UNITED STATES PATENT OFFICE.

PHILIP ALEXANDER MACKAY, OF NEWCASTLE, NEW SOUTH WALES,
AUSTRALIA.

METALLURGICAL FURNACE.

No. 799,745.

Specification of Letters Patent.

Patented Sept. 19, 1905.

Application filed April 29, 1903. Serial No. 154,796.

To all whom it may concern:

Be it known that I, PHILIP ALEXANDER MACKAY, a citizen of the United States, residing at Newcastle, in the county of Northumberland and Colony of New South Wales, Australia, have invented a certain new and useful Improvement in Metallurgical Furnaces, (Case No. 3,) of which the following is a full, clear, concise, and exact description, reference being had to the accompanying drawings, forming a part of this specification.

My invention relates to a metallurgical furnace, and more particularly to a furnace adapted to be used for the treatment of ores in which a distillation process is employed.

My invention is particularly well adapted for use in connection with the treatment of ores containing zinc, and I shall describe my invention as adapted for the treatment of such ores.

Zinc oxide is reduced by carbon (C) only after a temperature of about 1,300° centigrade is reached, the reaction being $ZnO + C = Zn + CO$; but zinc volatilizes at a temperature of less than 1,000° centigrade. Therefore the extraction of zinc is possible only by distillation and condensation.

In order to free zinc ores from water and carbonic acid, it is customary to first treat zinc ores—for instance, ores in which the sulfid of zinc (ZnS) is present—by calcination or roasting. There is a further reason why sulfid ores are roasted preliminary to distillation, which is that it is necessary to reduce by roasting the zinc sulfid (ZnS) to zinc oxide (ZnO) in order that it may later be acted upon by carbon. There have been a number of processes used to reduce the zinc oxide after this preliminary roasting—such as the old English process, the Silesian process, and the Belgian process—in all of which the principle has been the same. Taking as an example the Belgian process, it has been the practice to charge clay retorts with a mixture of the roasted and ground oxide and other minerals present and carbon in the form of coal or coke screenings in about equal proportions.

As is well understood by those skilled in the art the ores of zinc—such as zincite, calamine, and blende—contain many other substances besides pure compounds of zinc. Thus in addition to zinc sulfid blende contains sulfids of iron, lead, antimony, and cadmium. These impurities of course are more

or less reduced during the roasting process and are then charged into the retorts with the zinc oxid. The zinc ores also frequently contain the precious metals gold and silver. The charged retorts are then gradually heated. In case it has been desired to obtain bar-size or zinc-dust the retorts are provided with suitable condensers which condense the volatilized zinc which is distilled over.

Zinc oxid is now much used in the arts, and it is the practice to burn zinc in air to form fumes of oxid of zinc, which fumes are passed through a so-called "bag-room," which is a passage-way intercepted by suitable sheets of cloth adapted to collect the powdered oxid of zinc. Such zinc processes as heretofore carried on have been more or less limited in capacity, due to the difficulties incident to the use of retorts. It is very difficult to charge retorts which are of sufficient size to give satisfactory results. The retorts themselves are sooner or later destroyed by the reactions going on within. Such a retort-furnace is not well adapted for continuous operation.

My invention has for its object the provision of a suitable furnace for the reduction of roasted zinc ores, which by its construction and mode of operation is peculiarly well adapted for continuous operation and which by its design may be made to accommodate and successfully treat large quantities of ore.

The embodiment of my invention, which I shall herein describe, is intended for use where the product to be obtained is zinc oxid rather than metallic zinc. However, I do not wish to limit myself to the use of the furnace for this purpose or in this manner.

My invention will be clearly understood by reference to the accompanying drawings, in which—

Figure 1 is a plan view of a furnace constructed in accordance with my invention, one end being broken away to more clearly reveal the interior construction. Fig. 2 is a cross-sectional view taken on line 2 2 of Fig. 1. Fig. 3 is a cross-sectional view taken on line 3 3 of Fig. 1, and Fig. 4 is a partial cross-sectional view taken on line 4 4 of Fig. 3.

A furnace constructed in accordance with my invention may be built of fire-brick or any suitable refractory material. There are provided two sets of regenerators, each comprising a chamber 5, filled with suitable checker-work in the manner well understood

by those skilled in the art, and a second chamber 6, similarly filled with checker-work. The chambers 5 are connected, by means of the passage-ways 7 7, with valving mechanism 5 adapted to admit gas or other suitable fuel to either one or the other of these passage-ways. The chambers 6 6 communicate, by means of the passage-ways 8 8, with valving mechanism adapted to admit air to either one or the other 10 of the regenerator-chambers 6. The valving mechanism employed is adapted to cause the admission of fuel and air to the regenerator-chambers on one side of the furnace, the other set of regenerator-chambers being at that 15 time connected, by means of the passage-ways, with a suitable exhaust flue or chimney. Passage-ways 9 and 10 connect the regenerator-chambers on opposite sides of the furnace, these passage-ways including combustion-chambers 11 11, the purpose of which will be 20 hereinafter more fully explained. Interposed between adjacent combustion-chambers 11 11 are formed suitable reduction-chambers 12 12, these reduction-chambers being separated 25 from the combustion-chambers by walls as thin as practice will permit. The tunnels 13 13, passing underneath the rows of reduction-chambers, are provided with railways 14 14, upon which cars travel and into which the 30 residues from the reduction-chambers may be dropped upon opening the doors 15 15, which close the openings 16 16 in the bottoms of the reduction-chambers. Suitable covers 17 17 close openings in the tops of the reduction-chambers, through which openings the zinc 35 ores are charged into the reduction-chambers. Passages 18 18 connect the upper parts of the reduction-chambers with the flues 19 19, which lead, in case the furnace is to be operated 40 for the direct production of zinc oxid, to a combustion-chamber in which the hot volatilized zinc is burned with air to form fumes of zinc oxid. These zinc-oxid fumes are thereafter passed into a bag-room, where 45 the zinc oxid is deposited in the manner well understood by those skilled in the art.

The operation of a furnace constructed in accordance with my invention may be described as follows: The regenerative furnace 50 is operated in the well-known manner, in which gas may be supposed to enter through the passage 7 and air through the passage 8, the gas and air passing, respectively, through the checker-work in chambers 5 and 6, being heated by the heat retained in the regenerator-chambers. The gas entering through the chamber 5 flows through the passage-ways 9 to the combustion-chambers 11, while the heated air enters the combustion-chambers 60 through the passage-ways 10. The hot gas and air burn within the combustion-chambers 11 at a very high temperature. The hot products of combustion flow through the passages 9 and 10 on the other side of the furnace to 65 the passive regenerator-chambers 5 and 6, the

checker-work of which is heated thereby. The products of combustion pass through the passive regenerator-chambers and the passages 7 and 8 to an uptake-flue. (Not shown.) After the regenerators have been operated 70 for a suitable length of time in this direction the valving mechanism is reversed, so that the gas and air are admitted through the regenerator-chambers, which have just been heated by the hot products of combustion 75 from the combustion-chambers 11 11. The first set of regenerator-chambers are now connected with the uptake-flue, so that they may be heated by the hot products of combustion issuing from the combustion-chambers. 80

The operation of the regenerative furnace is well understood by those skilled in the art, and in and of itself I make no claim to the invention thereof.

The roasted zinc ores, from which it may have been desirable to remove cadmium in the manner described in my copending application, Serial No. 110,940, filed June 9, 1902, are charged, with carbon in convenient form, 90 into the reduction-chambers 12 12. Heat is transmitted through the relatively thin walls from the combustion-chambers 11 11 to the reduction-chambers 12 12. The carbon is thereby caused to unite with the oxygen of 95 the zinc oxid, and the zinc is volatilized and passes off through the openings 18 18 to the flues 19 19, which lead to a suitable combustion-chamber in which the volatile zinc is burned in air to form zinc-oxid fumes. As 100 above described, these fumes are then passed through a bag-room, in which the zinc oxid is collected. The residues remaining in the reduction-chambers after the distillation of the zinc are dropped through the openings 105 16 16 in the bottoms of the chambers 12 12, when they may be removed in suitable trams 110 cars running in the tunnels 13 13. The residues removed from the chambers contain such impurities as may have been present in the zinc ores, in addition to gold, silver, and lead.

It will be seen that by the arrangement shown the ores to be treated are passed through the furnace in a practically vertical line. This facilitates the handling of the 115 materials for the reason that the reduction-chambers may be charged from an elevated railway or suitably-placed hoppers. The residues are removed from the reduction-chambers largely by action of the force of 120 gravity.

The furnace is adapted for the burning of zinc as distilled off, as distinguished from furnaces of the prior art, in which the charge has been blown up with air. By this means 125 I am enabled to save lead or silver which may be present in the ores.

The furnace is particularly useful for the direct production of zinc oxid, as distinguished from the practice of the prior art, in which 130

zinc has been distilled off and condensed to form spelter, the spelter being afterward burned to form oxid.

While I have described the operation of my improved furnace as carried on in the production of zinc oxid, it will be apparent that it may be used for many other purposes—such, for instance, as the production of lead oxid.

Many other modifications and changes will be apparent to those skilled in the art, and I do not, therefore, wish to limit myself to the precise disclosure herein set forth; but,

Having described my invention, I claim as new and desire to secure by Letters Patent—

In a metallurgical furnace comprised in a unitary structure, the combination with parallel passages or chambers extending longitudinally along the center of the furnace, regenerative furnaces extending longitudinally along the sides of the furnace, passage-ways connecting the regenerative furnaces with the parallel chambers, partitions between the

chambers, each partition being hollow to form a left and right reduction-chamber having thin walls, oxidizing-chambers extending longitudinally over the regenerative furnaces, one at each side of the structure, passage-ways connecting the left reduction-chamber with the left oxidizing-chamber, passage-ways connecting the right reduction-chamber with the right oxidizing-chamber, an opening in the top of each reduction-chamber for receiving the products to be treated, a passage-way below each row of reduction-chambers, and a trap-door 15 at the bottom of each reduction-chamber by means of which the products of each of the reduction-chambers may be conveyed to each of the passage-ways below the reduction-chambers.

In witness whereof I hereunto subscribe my name this 24th day of March, A. D. 1903.

PHILIP ALEXANDER MACKAY.
